UNITED STATES PATENT OFFICE.

HAROLD H. SHOTWELL, OF CHICAGO, ILLINOIS, ASSIGNOR TO THE OPERADIO CORPORATION, OF CHICAGO, ILLINOIS, A CORPORATION OF ILLINOIS.

VARIABLE CONDENSER.

Application filed June 27, 1924. Serial No. 722,655.

The present invention has for its object to produce a simple and novel variable condenser having within the same means for securing a vernier adjustment without the use of a separate vernier plate, and without requiring that a knob be turned in opposite directions to secure first a rough adjustment and then a fine adjustment.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is an end or a front elevation of a device embodying the present invention; Fig. 2 is a section taken approximately on line 2—2 of Fig. 1, showing the device, together with a fragment of a panel on which the same is mounted; Fig. 3 is a section taken approximately on line 3—3 of Fig. 2; Fig. 4 is a section taken approximately on line 4—4 of Fig. 2; and Fig. 5 is a section taken approximately on line 5—5 of Fig. 1, only a fragment of the device being shown.

Referring to the drawings, 1 and 2 represent two metal discs held in fixed spaced relation to each other by means of three parallel rods, 3, 4 and 5 placed at equal distances apart near the peripheral edges of the discs. The rod 3 is in metallic contact with the discs and forms one terminal of the condenser. The rods 4 and 5 are insulated from the discs and one of them forms the other terminal of the condenser. The insulation between the rods 4 and 5 and the discs may take any usual or preferred form. As shown in Fig. 5, the rod 4 has thereon bushings 6 and 7, of insulating material, these bushings fitting into the enlarged openings in the discs through which the rod 4 passes and having enlargements or flanges at their outer ends to engage with the outer faces of the discs and thus hold the head 8 on one end of the rod and the nut 9 on the other end out of engagement with the discs. The rod 5 is mounted in a similar manner. The stationary plates 10 of the condenser are mounted on the rods 4 and 5, the plates being spaced apart by means of spacing washers 11 and being insulated from the discs 1 and 2 by means of insulating sleeves

12 and 13 surrounding the rods 4 and 5 between the two outer plates of the series and the discs. The plates 10 are in metallic contact with the rods 4 and 5.

The movable plates 15 that are intercalated with the stationary plates but out of contact therewith, are mounted upon and in metallic contact with a hollow shaft 16 extending at right angles to the discs between the same and at the centers thereof. The shaft is supported at one end in an elongated hub 17 projecting outwardly from the disc 1 and extends through this hub and is provided on its outer end with a pointer 18. The opposite end of the hollow shaft terminates a short distance from the rear disc 2 and has attached thereto a resilient spider 19 arranged at right angles to the axis of the shaft. In the arrangement shown, this spider has three radial arms. Mounted on the free end of each of the arms of the spider is a wheel 20 in the shape of a short frustum of a cone. The disc 2 is either recessed on its inner face or is made dish-shaped, the depression or recess being pointed by an annular wall 21 co-axial with the tubular shaft and inclined to form a track on which the inclined faces of the wheels 20 may run. Extending axially through the tubular shaft 16 is an actuating shaft 22 having on its outer end beyond the pointer 18, a knob 23 by means of which it may be turned. The inner end of the shaft 22 extends somewhat beyond the corresponding end of the surrounding shaft, and is provided with a small cone-shaped wheel 24 occupying the reverse position with respect to the wheels 20 and engaged at its periphery with the inclined peripheral surfaces of the wheels 20. It will be seen that if, when the parts are assembled, the resilient spider is placed under an initial tension, it serves to force the wheels 20 against the inclined annular track. It will also be seen that if the actuating shaft 22 is pushed or drawn in that direction in which it would move by pull upon the knob, the wheel 24 is drawn into intimate contact with the wheels 20. In order to place the wheel 24 in intimate engagement with the surrounding wheels 20 and hold it there, I have placed a set screw 25 at the center of the disc 2, the set screw being co-axial with the shafts. When the set screw is turned until it engages with the end of the shaft 22, any

further turning movement results in pressing the wheel 24 against the wheels 20, where it will remain until wear takes place. When wear occurs, it may be compensated for by simply adjusting the set screw. Since the set screw is intended to remain stationary, while the shaft 22 is adapted to be rotated, a locknut 26 is placed on the set screw to prevent it from being accidentally turned by the shaft. In the arrangement shown, a small ball 27 is placed between the inner end of the set screw and the end of the shaft 22, or rather the small wheel that forms the end of the shaft, thus reducing the friction.

15 When the knob is turned to adjust the condenser, the small wheel 24 acts on the wheels 20 to rotate the latter. Since the wheels 20 are in engagement with the stationary annular track 21, they can only rotate by rolling along this track. Consequently a rotation of the knob in either direction will produce a rotation of the tubular shaft and of the movable plates 15 that are attached to the shaft. However, since a 25 complete rotation of the tubular shaft can be caused only by the rolling of the wheels 20 along the entire circumferential length of the inclined track 21, since the small conical driving wheel 24 must turn more than once to effect a single rotation of the wheels 20, and since each of the wheels 20 must rotate more than once in order to make a complete circuit of the inclined track, the rate of movement of the tubular shaft and its attached plates is much less than the 30 rate at which the knob is turned. Consequently the operator is able to make fine 35 adjustments of the position of the movable plates of the condenser by turning the knob 40 through much greater angles. In other words, he may obtain a vernier adjustment without the manipulation of any other device than the single knob or handle. In the arrangement shown, the ratio of speed reduction 45 is more than eight to one but any desired ratio may be obtained by properly proportioning the diameters of the driving and driven wheels and of the annular track.

The hub 17 on the disc 1 may be employed 50 for the purpose of attaching the device to a panel. As shown in Fig. 1, the hub is externally screw-threaded at its outer end and is passed through a suitable panel 30; the panel being clamped between a spacing sleeve 31 55 surrounding the hub between the panel and the disc and a nut 32 screwed on the outer end of the hub.

It will thus be seen that I have produced 60 a simple and novel variable condenser having built into the same and forming a part thereof of a simple planetary gear mechanism adapt-

ed greatly to reduce the rate of movement transmitted by a driving member to a driven member; or in other words, a greatly decreased angle of movement of the movable 65 plates of the condenser for any given annular movement of the actuating knob or handle.

While I have illustrated and described with particularity only a single preferred 70 form of my invention, I do not desire to be limited to the exact structural details thus illustrated and described; but intend to cover all forms and arrangement which come within the definitions of my invention constituting the appended claims.

I claim:

1. In combination, a supporting frame having a wall provided with an annular track in the form of a short frustum of a cone, a tubular shaft co-axial with said track, a resilient device yieldable in the direction of the axis of the shaft fixed to the latter in the vicinity of said wall, a group of wheels mounted on said device so as to be capable of rotating about axis parallel with the axis of the shaft, the wheels being so disposed that all of them are in rolling contact with said track, an actuating shaft extending through the tubular shaft, a frusto-conical wheel on said actuating shaft in the space between and in engagement with the aforesaid wheels, the larger end of the wheel on the actuating shaft being directed toward said wall, and means for exerting a pressure 95 on said actuating wheel in a direction tending to force it away from said wall.

2. In combination, a frame having a wall provided on the inner side with an annular track in the form of a short frustum of a cone, a movable device supported within said frame so as to be rotatable about the axis of said track, a spider of spring material fixed to said device and lying adjacent to and parallel with said wall, a group of 100 wheels mounted on said spider at equal distances from said axis and each rotatable about its individual axis, the aforesaid wheels being in the form of frustums of cones each making a line contact with said track, an actuating wheel in the form of a frustum of a cone disposed oppositely to the other wheels in the space between and in contact with the latter, means for rotating the actuating wheel, and an adjustable stop 105 engaged with that face of the actuating wheel directed toward said wall to hold this wheel in contact with the other wheels.

In testimony whereof, I sign this specification.

HAROLD H. SHOTWELL.
